(57) **CLAIM**

The ornamental design for a chair, as shown and described.

DESCRIPTION

FIG. 1 is a perspective view of a chair in accordance with the present design;

FIG. 2 is a front view of the chair illustrated in FIG. 1;

FIG. 3 is a rear view of the chair illustrated in FIG. 1;

FIG. 4 is a right side view of the chair illustrated in FIG. 1;

FIG. 5 is a left side view of the chair illustrated in FIG. 1;

FIG. 6 is a top view of the chair illustrated in FIG. 1; and,

FIG. 7 is a bottom view of the chair illustrated in FIG. 1.

The broken lines showing parts of a chair are for the purpose of illustrating portions of the chair that form no part of the claimed design.

1 Claim, 7 Drawing Sheets
